UNITED STATES PATENT OFFICE.

JULIUS JOSEPH DRAWE AND WALTER JOSEPH TURNBULL, OF NEW ORLEANS, LOUISIANA.

BED.

No. 905,856.

Specification of Letters Patent.

Patented Dec. 8, 1908.

Application filed October 25, 1907. Serial No. 399,200.

To all whom it may concern:

Be it known that we, JULIUS JOSEPH DRAWE and WALTER JOSEPH TURNBULL, citizens of the United States, residing at 5 New Orleans, in the parish of Orleans and State of Louisiana, have invented certain new and useful Improvements in Beds; and we do hereby declare the following to be a full, clear, and exact description of the invention, such as will enable others skilled in the art to which it appertains to make and use the same.

This invention relates to improvements in beds, and is primarily designed to provide a 15 bedstead of metal or other suitable material, which may be utilizable either with a box spring for supporting the mattress or with the usual or rigid bed slats as said mattress support.

20 Broadly, the invention consists in providing reversible rails associated with mechanism for forming an interlock between the bed posts and the ends of said rails, one operating face of said rails being adapted to 25 form a horizontal support for the frame of the box spring, and the inside of said rails being adapted to receive the usual form of wooden slats.

Other objects and advantages and the 30 details of construction will appear in the following description, the distinctive features of the invention being more succinctly set forth in the claims.

While the invention is not restricted to the 35 exact details shown and described, still for the purpose of disclosure reference is had to the accompanying drawings illustrating a practical embodiment of the same, in which like letters designate the same parts in the 40 several views, and in which—

Figure 1 is a perspective view of a bedstead with our invention applied thereto, and showing the hollow or inside portion of the reversible rails in position to receive the 45 rigid slats. Fig. 2 is a fragmentary enlarged view showing one of the reversible rails fitted in position, and showing another reversible rail removed to illustrate the manner of securing the rails to the corner post. Fig. 3 is 50 a horizontal central section through the corner post and a pair of the reversible rails attached thereto, and showing the end of one of the rigid slats in position. Fig. 4 is a fragmentary sectional view showing the method 55 of securing the slats to the bed rail. Fig. 5

is a view looking inwardly towards one of the corner posts in the direction indicated by the arrow in Fig. 3 with the bed rails detached. Fig. 6 is a local sectional view on the line 6—6 of Fig. 5, and looking upwardly in the 60 direction of the arrows. Fig. 7 is an interior elevation of one of the reversible rails, the rail being broken away for simplicity of illustration. Fig. 8 is a fragmentary view in 65 side elevation showing a bracket or brace interposed between the bed post and the rail to insure greater rigidity to the parts, a portion of the bed post and bracket being broken away to show the means of connecting them together, and Fig. 9 is a view similar to Fig. 5, but with the bed rails attached to the corner lock in a reverse position to that previously shown, and forming a support for a box spring.

In carrying out the invention there is first 75 provided what may be termed a corner lock. Referring more particularly to Figs. 1 to 6, this corner lock consists in a body portion 1, supported by a bed post 2, which latter may form an integral part of said body portion, 80 or may be separable therefrom. This body portion is provided with two inside faces disposed at right angles to each other, and these inside faces are recessed, and projecting therefrom are tongues 3 and 4, which 85 may form an integral part of the body portion, or may be otherwise secured therein. These tongues 3 and 4, at their base, are of smaller dimensions than the spaces between the walls of said recessed faces, and form 90 with said walls the upper and lower horizontal recesses 5 and 6 and the vertical recess 7, the position where the upper and lower horizontal recesses come together being illustrated by the edge 8, more clearly shown in Figs. 5 95 and 6. The projecting ends of the tongues, and 6. The projecting ends of the tongues, which are disposed at right angles to each other, are provided with the transverse holes 9, and the vertically-projecting pins 10, the object of which holes and pins will later be 100 referred to.

Referring more particularly to Figs. 1, 2, 3 and 7, there is shown hollow rails, which may be termed reversible rails for convenience. These rails consist of two sides disposed at 105 right angles to each other, forming a hollow internal support when disposed in the position shown in these figures, 11 in these views showing the lower horizontal wall, and 12 showing the vertical outside wall. These rails may 110

be provided adjacent their ends with the partitions 13, forming a housing for the reception of the tongues of the corner locks. The walls 11 of the rails may also be provided with a plurality of apertures shown at 14, in Figs. 1 and 4, which series of holes are adapted to receive pins 15 formed on rigid slats 16 for holding the slats in place. Said rails are also provided on each wall with a pair of apertures 17 and 18, disposed within the recesses formed between the partitions 13 and the end of the rails, and the apertures 17 being formed in the wall 12 with the apertures 8 in the wall 11.

15 In Fig. 8 there is illustrated a suitable bracket or brace to assist in making the parts more rigid, and this bracket may consist in the angularly-disposed arms 19 secured to the bed rails by a pin 20, and provided at their ends with pintles 21 fitting in the sockets 22 formed in the bed post.

20 In Fig. 9 the bed rails are shown in their reverse position, the walls 11 of said rails being then disposed in vertical planes, with the walls 12 in horizontal planes, and the latter walls forming a support for a box spring, the bed slats being then dispensed with.

25 Various means may be employed for interlocking the reversible rails with the corner lock, and for the purpose of illustration several may be referred to. For instance, as shown in Fig. 1, and on one tongue in Fig. 2, the ends of the rails are secured to the corner lock by means of a headed bolt 23 passing through the aperture 17 in the rail, and the hole 9 in the tongue, the threaded end of the bolt being provided with a nut 24. If the bolts are objectionable, 30 pins may simply be used in their place. If either of these fastening means is not desirable, the reversible rails may be provided with the arrangement shown in Fig. 3, wherein 25 designates a spring member secured at one end, as at 26, to the rail, and provided at its other end with a pin 27 passing through the aperture 17 and into the hole 9, the pin 27 in this case taking the place of the bolt 23 or its equivalent pin. 35 In all of these constructions, the vertical pins 10 may be used or not, as desired, although they form a more rigid connection between the parts. When used, and when the rail is in the position shown in Figs. 1 to 40 7, the downwardly-projecting pin 10 fits in the hole 18, while in the reverse position shown in Fig. 9, the upper pin 10 fits in the hole 18 at the other end of the rail. In assembling the parts into position for use with bed slats, the end edges of the walls 11 and 12 are fitted in the horizontal and vertical slots 6 and 7, respectively, and the rails secured to the tongues 3 and 4, as previously described. When, however, the rails are 45 reversed for use with a box spring, the end

edges of the walls 11 and 12 are similarly inserted in the slots 5 and 7, respectively, and the parts secured as heretofore described.

What we claim is:—

1. In a bed, the combination with a plurality of corner locks, comprising a body portion having inwardly-disposed faces at right angles to each other with tongues projecting from said faces, each face of said body portion being provided with a pair of horizontal recesses and a vertical recess disposed around the base of said tongues, a plurality of reversible rails comprising walls disposed at right angles to each other, the end edges of said walls being adapted to fit in said horizontal and vertical recesses, and means for securing said rails to said tongues when the end edges thereof are inserted in said slots, substantially as described. 75 80

2. In a bed the combination of a plurality of corner locks comprising a body portion and a pair of tongues disposed inwardly at right angles to said body portion, a plurality of rails, means for detachably securing said rails to said body portion, means for detachably securing said rails to said projecting tongues in reversed positions and independent means for connecting said rails with said corner posts, substantially as described. 85 90

3. The combination of a plurality of bed posts and corner locks carried thereby, a plurality of reversible rails, means for securing said reversible rails in either of their reversible positions to said corner locks, and independent means for connecting said rails with 95 said corner posts, comprising angularly-disposed arms carried by said rails and projecting above and below said corner locks, and provided at their projecting ends with pintles operating in sockets cut into said posts, 100 105 substantially as described.

4. In a bed the combination of a plurality of corner locks comprising a body portion and a pair of inwardly disposed tongues, said body portion being provided on each vertical face with a pair of horizontal recesses and a vertical recess and each of said tongues having transverse apertures therethrough, a plurality of reversible rails formed by a pair of angularly disposed walls and each of said 110 115 walls being provided near their ends with apertures adapted to register with the apertures in said tongues, and means for detachably securing said rails to said tongues comprising securing pins passing through said alining apertures, substantially as described. 120

5. In a bed the combination of a plurality of corner locks comprising a body portion having inwardly disposed faces at right angles to each other with tongues projecting 125 from said faces, each face of said body portion being provided with horizontal slots 5 and 6 and a vertical slot 7 disposed around the base of said tongues and vertical pins 10 carried by said tongues and said tongues be- 130

ing provided with the lateral apertures 9, a plurality of reversible rails having angular walls provided with non-aligned apertures 17 and 18 coöperating with said pins 10 and 5 apertures 9 and fastening pins 23 coöperating with said apertures, substantially as described.

In testimony whereof, we affix our signatures, in presence of two witnesses.

JULIUS JOSEPH DRAWE.

WALTER JOSEPH TURNBULL.
